UNITED STATES PATENT OFFICE

LAWRENCE M. PERSONS, OF DES MOINES, IOWA, ASSIGNOR TO COOK ELECTRIC COMPANY, OF CHICAGO, ILLINOIS, A CORPORATION OF ILLINOIS

HEAT MOTOR

Continuation of application Serial No. 37,091, filed June 15, 1925. This application filed January 10, 1929. Serial No. 331,690. Renewed January 27, 1933.

My invention relates to thermally controlled vapor motors and more particularly to a vapor motor of this type adapted to be influenced by the thermal expansion of a volatile fluid.

Vapor motors constructed in a manner to be influenced by the thermal expansion of a volatile fluid usually consist of an expandable and contractible vessel cooperating with a suitable source of heat arranged to heat the fluid and increase the pressure within the vessel. Numerous factors obviously enter into the timing of the movement of the vessel. It has been found that after the initial movement, the vessel continues at a rather rapid rate to expand, but considerable difficulty is experienced in avoiding an undesirable lag before the initial movement begins. On the other hand, it is difficult, due to this initial time lag, to thereafter control the movement in proper timed relation, which is not only desirable but essential in the operation of various regulators.

One of the objects of the present invention resides in the provision of an improved form of vapor motor having a heating tube or boiler in communication with an expandable and contractible vessel and a source of heat which are so arranged as to first rapidly volatilize a limited amount of the liquid, thereby rapidly increasing the pressure within the vessel and accelerating the initial movement of the vessel.

More specifically, this result may be accomplished by arranging the electrical resistance wire or heat coil about the tube or boiler so that the turns of the heat coil are spaced more closely together at the upper end where the volatile liquid first starts to expand. Accordingly, the pressure in the tube or boiler rapidly increases at the start and thereafter builds up more uniformly and quickly.

I have found that by providing approximately three times the number of turns of the heat coil at the upper end of the tube, it is possible to secure complete predetermined expansion of the vessel in one-third of the time heretofore required.

Other objects and advantages of the in-

vention will be apparent from the following description when taken in connection with the accompanying drawings in which:

Figure 1 is a view partly in section and partly in elevation of a heat motor embodying my invention;

Fig. 2 is a similar view of another embodiment of my invention; and

Figs. 3 and 4 are also similar views illustrating different embodiments of the invention.

In the drawings wherein for the purpose of illustration there are shown several preferred embodiments of my invention, the vapor or heat motor may comprise an expandable and contractible vessel 1 having a volatile liquid therein and a tube 2 or boiler in communication with the vessel and which receives a portion of the liquid.

This vessel 1 is preferably shown as comprising a well known form of bellows which readily expands or contracts upon an increase of pressure therein. Tube 2 is closed at one end and in communication at the opposite open end with vessel 1. As to the specific form of heating device that may be used, it is obvious that the source may be an electrical resistance coil or heating flame conveniently located at or adjacent to tube 2. A heating zone will be provided within tube 2 for heating the volatile liquid and driving it into vessel 1 by volatilization. The pressure within the tube will be gradually increased until the level of the liquid is depressed, whereupon further volatilization stops as the liquid is driven out of the heating zone. It is by this means that a predetermined expansion or movement of vessel 1 may be effectively obtained and held without danger of the pressure within building up to a point where the vessel will burst. In so far as this subject matter is concerned the present application is a continuation of co-pending application Serial No. 37,091, Filed June 15, 1925.

The vapor motor shown in Fig. 1 includes the expandable and contractible vessel 1 having one end closed by a plate 3 to which may be attached a movable actuating rod 4, if this end of vessel 1 is arranged to be mov-

able. A plate 5 suitably closes off the opposite end of vessel 1, this plate being provided with an opening 6 into which is seated cup 7 that may extend into vessel 1. Cup 5 7 may then extend upwardly by means of a neck 8. This neck 8 communicates with the lower open end of tube 2 and is hermetically sealed thereto at 9.

A sheet of mica 10, or other suitable insulation, may be wrapped about tube 2 so as to provide electrical insulation for an electrical resistance wire or heat coil 12 wound about the tube. Terminal bands 13 and 14 are clamped at proper points along tube 2 15 to receive the ends of heat coil 12. While I have shown a heat coil of an electrical circuit for furnishing heat or acting as a source of heat for the vapor motor, it will be understood that any suitable heating means 20 may be employed.

I find that by applying the heat to tube 2 in a certain manner, the volatilization of the liquid and the consequent expansion or movement of vessel 1 may be accurately controlled under a wide set of conditions. That 25 is to say, the time required to complete the full stroke of a predetermined movement of vessel 1 may be ascertained and accordingly controlled so that the vapor motor may be used in regulators requiring practically any given set of timed operations.

To accomplish this feature, the windings of heat coil 12 may be so spaced as to concentrate or localize the heat, either initially 35 or during subsequent operation, along tube 2 and thereby effect volatilization of a portion of all the liquid in a given time. In the present disclosure, it is found that spacing the windings of heat coil 12 more closely 40 together at the top of tube 2 causes a relatively quick volatilization of the liquid at the upper end of the column so that rapid building up of pressure at this point takes place. Accordingly, the level of the liquid 45 is rapidly depressed to expand or move a greater volume of the liquid into the vessel to accelerate initial expansion. On the other hand, this rapid building up of pressure is continued after once started, so that 50 the full stroke may be completed in a relatively short time.

In the present instance, I have disclosed three times the number of windings of heat coil 12 along the upper third of the length 55 of tube 2, and by this arrangement, I am able to obtain complete expansion of vessel 1 in one-third of the time which is normally required where such spacing is not employed. To illustrate, if tube 2 is three 60 inches in length, the first inch at the top of tube 2 may be provided with fifteen turns, while the remaining lower two inches may each be provided with five turns.

It seems that the aforesaid rapid expanding action or movement of vessel 1 in less

time is the result of more quickly boiling or heating a small volume of the volatile liquid at the outset so that with the boiling point once obtained at the level of the column of the liquid in tube 2, more rapid and 70 continuous volatilization of this column of liquid can be maintained until finally depressed into the vessel—or out of the heating zone.

It will be understood that the specific example given of the manner in which the turns of heat coil 12 are spaced is merely 75 illustrative of the invention, and accordingly may be varied to meet a given set of conditions in the timing of the movement 80 of vessel 1.

In Fig. 2, the embodiment of the invention illustrates a structure wherein vessel 1 is contracted instead of expanded upon heating of the volatile liquid in tube 2. In 85 this instance, vessel 1 is hermetically sealed to a plate 15 extending outwardly from its lower edge so as to receive a housing 16 seating thereover and enclosing vessel 1. This arrangement provides a closed expansion chamber 19 between vessel 1 and housing 16 so that any increase of pressure within this chamber will compress vessel 1 to move an actuating arm 17 downwardly. 90 Tube 2 may communicate by means of a coupling 18 with chamber 19 at one side of housing 16.

Another preferred form of the invention is illustrated in Fig. 3. A chamber 20 is furnished by housing 21 in which vessel 1 100 is received so that if desired the fluid in chamber 20 may be used to keep the volatile liquid in vessel 1 in a liquid state and thereby prevent continued volatilization thereof after its level has been depressed into vessel 1. 105 This method of maintaining the predetermined expansion of vessel 1 may be used where driving the level of the liquid out of the heating zone in tube 2 is not relied upon. In this device, vessel 1 is hermetically sealed at 24 to plate 25. Tube 2 is also carried by plate 25 and communicates with vessel 1 by means of a hollow tube 26. Plate 25 110 serves to carry the vapor motor as a unit capable of ready attachment to various 115 forms of regulators.

The embodiment shown in Fig. 4 may be likewise carried as a detachable unit, having tube 2 arranged transversely however, to the axis of vessel 1. A coupling 30 connects tube 2 with the interior of vessel 1. 120 By arranging tube 2 in this manner any air trapped in the upper end of the tube during sealing of the volatile liquid therein may be led through coupling 30 into the interior of vessel 1 by inverting the device after assembly. This air will pass through openings 31 in coupling 30 and remain confined about the outer portions of the different sections of vessel 1. In view of the ar- 125 130

angement of these sections, it is impossible for this air to travel back into tube 2. The advantage of removing any such air that may be trapped in the sealing of tube 2 resides in the fact that initial heating of the liquid is not thereby hindered, inasmuch as the heat may be applied directly to a greater volume of liquid.

Without further elaboration, the foregoing will so fully explain the gist of my invention, that others may, by applying current knowledge, readily adopt the same for use under varying conditions of service, without eliminating certain features, which may properly be said to constitute the essential items of novelty involved, which items are intended to be defined and secured to me by the following claims.

I claim:

1. A heat motor comprising an expandable and contractible vessel having a volatile liquid therein, a heating device therefor and a heat coil wound about said heating device, said heat coil being arranged with the windings at the top of said heat coil more closely spaced to accelerate initial heating of said liquid.

2. A heat motor comprising an expandable and contractible vessel having a volatile liquid therein, a heating device therefor and a heat coil wound upon said heating device, the windings of said heat coil along the upper third of the length of said heating device being spaced apart substantially one-third the distance between windings along the remaining portion of said heating device whereby to accelerate initial heating of said liquid.

3. A heat motor comprising an expandable and contractible vessel having a volatile liquid therein, and a heating device therefor having provisions for generating a greater heat within a limited area of said heating device whereby to accelerate vaporization of said liquid and effect more rapid expansion of said vessel.

4. A heat motor comprising an expandable and contractible vessel having a volatile liquid therein, a heating device therefore, and a heat coil wound about said heating device, the windings of said heat coil being more closely spaced at the top of said heating device whereby to accelerate initial heating of said liquid and thereafter more gradual heating to secure rapid expansion of said vessel.

5. A heat motor comprising an expandable and contractible vessel and a tube closed at one end and in communication therewith at the opposite end, said vessel and said tube having a volatile liquid therein, and an electrical heat coil wound about said tube, the windings of said heat coil being spaced more closely together at said closed end whereby

initially to heat said volatile liquid at a greater rate.

6. A heat motor comprising a vessel having a volatile liquid therein and means for heating the liquid for effecting a movement of said vessel, the arrangement of said heating means being such that a limited amount of said liquid will be first volatilized to accelerate the initial movement of said vessel.

7. A heat motor comprising an expandable and contractible vessel having an expandable liquid therein, suitable supporting means for said vessel, a heating device therefor comprising a substantially closed tube communicating at one end with said vessel, and mounting means arranging said tube substantially transversely with respect to said vessel.

8. The combination with suitable supporting means, of a heat motor mounted thereon and comprising a closed body filled with an expandable liquid, said body having a corrugated section expandable longitudinally by the pressure of the liquid, a relatively inextensible section having a heating coil surrounding the same, and a coupling member between said sections, said coupling member arranging said sections in relative right angular positions.

In witness whereof, I have hereunto subscribed my name,

LAWRENCE M. PERSONS.
